UNITED STATES PATENT OFFICE.

JOHN A. BAUER, OF BOSTON, MASSACHUSETTS, ASSIGNOR TO THE LAMSON COMPANY,
OF SYRACUSE, NEW YORK, A CORPORATION.

SIGNAL-ACTUATING DEVICE FOR DISPATCH SYSTEMS.

Original application filed August 10, 1922, Serial No. 580,883. Divided and this application filed
February 3, 1923. Serial No. 616,766.

To all whom it may concern:

Be it known that I, JOHN A. BAUER, a citizen of the United States of America, and resident of Boston, in the county of Suffolk and State of Massachusetts, have invented new and useful Improvements in Signal-Actuating Devices for Dispatch Systems, of which the following is a specification.

This invention pertains to carrier dispatch systems and relates more particularly to central station apparatus therefor.

One type of central station arrangement which has given very satisfactory results comprises a desk having longitudinally distributed carrier delivery terminals all of which deliver their carriers upon an endless belt or other conveyer by means of which they are moved lengthwise of the desk for delivery to the cashiers or charge authorizers. Commonly the cashiers and charge authorizers sit at opposite sides of the desk and the cash and credit carriers move along the desk in two independent streams, switching devices being provided at suitable intervals for diverting the carriers into open troughs down which they slide to the stations of the several attendants. Arrangements such as above outlined are generally satisfactory and give good service in most cases, a typical example of such a central station installation being disclosed in the patent to Whittier, No. 1,365,428, January 11, 1921. In certain situations, where by reason of limitation of space it is not possible to seat operatives at both sides of the desk, or when it is found expedient to have one set of attendants, as for example the charge authorizers, under closer supervision of the auditor or other responsible authority, it is desirable to deliver all of the carriers moving along one side of a desk to a relatively remote point, for instance, another floor of the building, where they may be distributed in any suitable manner among attendants there stationed, an arrangement designed for this purpose being more specifically disclosed in my copending application, Serial No. 580,883, filed Aug. 10, 1922, of which this is a division, such arrangement also comprising as an element an inclined open trough or chute along which the carriers are guided toward the entrance to a pneumatic transmission tube.

Whenever, as in the above example, in a

conveyer system an inclined open trough or chute is employed for guiding carriers, particularly if the chute be of tapering form or be restricted at its delivery end, there is the possibility that by the sticking or clogging of a carrier descending the chute, succeeding carriers will be caused to ride up upon such stationary carrier and perhaps spill out over the sides of the chute, or if remaining within the chute cause a general jam and suspension of traffic in the system. The principal object of the present invention is to provide a signal device applicable to a conveyer chute or trough and adapted to announce any accidental piling up or jamming of the carriers therein, thus giving notice of such occurrence to the person or persons responsible for keeping the system in operative condition.

For convenience in illustration, the present invention has been shown as applied to a central station apparatus of the general type disclosed in the above noted patent to Whittier, but it is to be understood that in its broader aspects it is applicable to carrier dispatch systems generally, whether of the pneumatic type or not.

In the accompanying drawings:

Fig. 1 is a fragmentary side elevation of a conveyer chute constructed in accordance with the present invention and provided with the improved signal actuating device.

Fig. 2 is a fragmentary side elevation of the discharge end of the chute of Fig. 1 having certain portions broken away to show more clearly the details of the signal actuating device, and also showing the end of a transmission tube as secured to the extremity of the chute.

Fig. 3 is an end elevation of the lower extremity of the chute showing the signal actuating devices but omitting the transmission tube.

Fig. 4 is a fragmentary plan view of the chute and the supporting means for the signal actuating devices also omitting the transmission tube.

Fig. 5 is a fragmentary side elevation to smaller scale showing the application of the chute with its signal actuating devices to a central station desk of known construction; and

Fig. 6 is a vertical cross section on a line such as 6—6 of Fig. 5.

Referring more particularly to Figs. 5 and 6 inclusive, a central station apparatus of the general type disclosed in the patent to Whittier, above referred to, is shown. This apparatus comprises one or more desks each having an elongate support 2 upon which two series of carrier delivery terminals 3, 4 are mounted. Upon either side of the support 2 elongate open troughs 5, 6 are arranged, the bottoms of which are formed by endless belts 7, 8 respectively. These belts are constantly moved in the direction of the arrow A in Fig. 5 by means of a suitable motor arranged below the desk. The transmission tubes 10 leading from the various substations are provided with automatic separators 11 of usual form which segregate the charge and cash carriers and deliver them into the terminals 3, 4 respectively from which they are discharged onto the belts 7 and 8. Upon one side of the desk, stations for the charge authorizers are arranged, and this side of the desk is furnished with a longitudinally extending shelf or table 12 onto which the carriers moving along on the belt 7 may be delivered by means of inclined chutes such as 13 provided at their upper ends with deflectors 16 having actuating handles 17. By suitably setting a deflector, carriers moving along the belt may be caused to diverge from their normal path and to pass down the corresponding chute 13 onto the table 12. The opposite side of the desk is provided with stations for the cashiers and may be in all respects similar to the side at which the charge authorizers are seated, the carriers moving along the belt 8 being diverted from their normal path by suitable deflector devices and deposited upon the table in front of the several cashiers. The vertical partitions or panels 15 which define the outer sides of the troughs 5, 6 respectively are provided with openings 18 through which the operators, after the proper transaction has been made, may drop the carrier onto an endless belt 19 which extends centrally of the table and by means of which the carriers are conveyed to a table 19^a where the return operator is seated, who places the carriers in the proper receiving openings of the return transmission tubes 21.

The above described arrangement is in common use and ordinarily is adequate for all purposes but in some establishments it is at times found desirable for various reasons to cause all the carriers moving along one of the belts 7 or 8 to be delivered directly to a common point removed from the desk at which they are first delivered.

As herein disclosed the carriers moving along the belt 7 may all be delivered at such a distant point and for this purpose an open trough or inclined chute 22 having a deflector 23 is provided at a point adjacent

to the right hand end of the desk, as viewed in Fig. 5. This trough or chute 22 is furnished with lateral flanges 24, 25 (Fig. 4) by means of which it may be secured to the panel 15. The trough or chute comprises the curved side walls 26, 27 and the inclined bottom wall 28. The side walls 26, 27 converge toward the lower end of the chute where the side and bottom walls are so formed as to provide a channel or passage of substantially circular cross section, the side walls being continued upwardly to form a sleeve-like member 29 which is split longitudinally as indicated at 30. Bosses 31, 32 project from the sleeve at either side of the split and are provided with aligned openings for the reception of a clamping screw 33. This sleeve member with its screw thus constitutes a clamp for the receiving end 34 of a pneumatic transmission tube 35 leading to any desired point.

The boss 31 is continued upwardly to provide a bracket 36 having a bearing at 37 in which a pivot pin 38 is secured. This pivot pin serves as the fulcrum for a bell crank lever having a curved arm 39 constituting a feeler whose free extremity is positioned slightly above the normal path of movement of carriers such as 40 moving along the trough or chute and into the entrance 34 of the transmission tube. This bell crank lever also comprises the arm 41 which underlies the free extremity of a curved spring 42 whose other end is secured at 43 to a block 44 of insulating material secured to the bracket 36. The spring 42 is provided with an electrical contact element cooperating with a second contact element carried at the end of a resilient member 45 secured at 45^a to the block 44, the contact elements being normally spaced apart. The springs 42 and 45 are electrically connected to binding posts 46, 47 respectively from which conductor wires 48, 49 extend. These conductor wires form parts of a suitable electrical circuit comprising a sounding device or other signal such for example as a bell B whereby upon completion of the circuit between the contact elements carried by the springs 42 and 45, an alarm will be given.

If it be desired to deliver all of the charge carriers to a remote point, the deflectors 16 corresponding to the several chutes 13 are positioned to cover the entrances to the respective chutes while the deflector 23 is set as indicated in Fig. 1. When thus arranged, all of the carriers delivered from the bank of terminals 3 will be swept from the belt 7 by the deflector 23 and will slide down the bottom wall 28 of the chute 22. As the carriers reach the lower end of the chute they pass into the receiving end 34 of the pneumatic suction tube 35. This suction tube may be of any usual type such for example as is indicated by the numeral 4 in

the patent to Libby No. 966,576, filed August 30, 1910 and by means of the tube 35 the carriers may be delivered at any desired point where they may be distributed to operators by means of a moving belt, inclined, chute, or in any other desired manner.

If during the operation of the device as above described, a carrier should for any reason become stalled or jammed in the entrance to the tube 35 so that succeeding carriers would ride up thereon as indicated in broken lines at 50 in Fig. 2, one of the improperly placed carriers would contact with the feeler arm 39 of the bell crank lever, thus swinging the lever to the position of Fig. 2 and completing the electrical alarm circuit through the spring members 42 and 45. The person responsible for maintaining the system in operative condition would thus be notified and the obstruction removed. While the alarm device forming the subject-matter of the present invention as herein illustrated is applied to the delivery end of a tapering and downwardly inclined chute discharging into the end of a suction tube, the invention is not limited to such specific application or location of the signal actuating elements but is capable of use with chutes or troughs of other specific shape or arrangement and irrespective of the type of carrier or of the element into or onto which carriers emerging from the chute or trough may be delivered.

What I claim and desire to secure by Letters Patent of the United States is:

1. A carrier dispatch system having a central station comprising a trough along which carriers may move, said trough having sides gradually merging into a tubular sleeve at its delivery end, a conveyer tube secured to the delivery end of the trough for receiving carriers therefrom, and signal means adjacent to the tubular delivery end of the trough for indicating the clogging of the delivery end of the trough with carriers.

2. A carrier dispatch system comprising a chute for guiding carriers, the terminal portion of the chute being of tubular form, a conveyer tube secured to the tubular end of the chute, a movable member associated with the terminal portion of the chute and comprising a feeler element positioned above the normal path of movement of carriers along the chute, and means operable by said feeler upon contact therewith of an abnormally positioned carrier in the chute, for actuating a signal device.

3. A carrier dispatch system comprising a central station having a guideway for carriers, an open trough having converging sides which diverge from said guideway and merge into a tubular sleeve at the delivery end of the trough, a pneumatic conveyer tube secured to said sleeve for receiving carriers from the smaller end of the

trough, and a lever device arranged at that part of the trough where its sides merge into the sleeve, said lever constituting an element of a signalling system whereby to give warning of the clogging of such smaller end of the trough with improperly positioned carriers.

4. A carrier dispatch system comprising a central station apparatus having an inclined open trough for carriers, said trough having converging sides, a conveyer for receiving carriers from said trough, a movable member depending into the open end of the trough a distance permitting normally positioned carriers to pass freely beneath it but to be struck by carriers riding upon others, and contact means engageable by said movable member for completing an alarm circuit to indicate abnormal position of carriers in said trough.

5. A carrier dispatch system comprising a chute having side walls, a bracket carried by one of said walls, a lever pivotally mounted upon the bracket and having a depending arm positioned above the chute but spaced from the path of normally positioned carriers in the chute, and a pair of normally separated contacts forming terminals of an electrical signalling system, said lever having a second arm operable to move said contacts into engagement to close the circuit upon actuation of the first arm by a misplaced carrier in the chute.

6. A carrier dispatch system comprising a central station having a guideway, means for moving carriers therealong, a trough diverging from said guideway, said trough being of smaller cross section at its discharge than at its receiving end, a conveyer tube connected to the discharge end of the trough, and a lever having an arm depending into the trough at a point adjacent to its smaller end, the end of said arm being spaced from the bottom of the trough a distance slightly greater than the diameter of a carrier, said lever being constructed and arranged to complete a signal circuit when moved by a carrier improperly positioned in the trough.

7. A carrier dispatch system comprising a chute having spaced side walls, a boss projecting from the upper part of one of said walls and a bracket integral with the boss, a lever pivotally supported upon the bracket and having an arm overhanging the trough, an insulating block mounted on the bracket, a pair of normally spaced contact elements supported by the block, said lever having a second arm engageable with one of said contacts for moving it toward the other contact, and an electrical alarm system of which the contacts constitute terminals.

8. A carrier dispatch system comprising in combination a chute, an insulating block

carried by the chute, a contact supporting arm secured to the block, a second and resilient arm secured to the block and having a contact element engageable with but normally spaced from the first contact, and a lever having an arm engageable with said resilient arm for bringing the contact ele-

ments into engagement and a second arm overhanging the chute and actuatable by an abnormally positioned carrier therein. ¹⁰

Signed by me at Syracuse, New York, this thirty-first day of January, 1923.

JOHN A. BAUER.
